UNITED STATES PATENT OFFICE

MIKAEL VOGEL-JORGENSEN, OF COPENHAGEN, DENMARK, ASSIGNOR TO F. L. SMITH & CO., OF NEW YORK, N. Y., A CORPORATION OF NEW JERSEY

CONVEYING FINE-GRAINED MATERIALS

Application filed July 14, 1931, Serial No. 550,899, and in Great Britain March 31, 1931.

This invention relates to the conveying of cement, coal dust, cement raw meal, and similar fine-grained materials in which the material is forced by compressed air from a closed tank through a conveyor pipe or conduit.

The object of the invention is to make it possible to control the speed of conveying and at the same time to prevent the conveyor pipe from being clogged or obstructed and to avoid overloading of the air compressor.

In accordance with the invention there is provided between the pipe for supplying compressed air to the tank and the pipe for conveying the material from the tank a by-pass pipe fitted with a valve which, at a predetermined pressure, allows compressed air to pass through the by-pass pipe without passing through the tank. Thereby it is ensured that the pressure of the compressor does not exceed a predetermined degree, permissible for the compressor, while by adjusting the load on the valve the speed of conveying can be adapted to the requirements at any time.

The single figure of the drawing is a dia-grammatic view illustrating the invention.

The material to be conveyed and contained in a closed tank 1 is forced from the tank through a conveyor pipe 2 by compressed air supplied by a compressor 3 and delivered into the tank through a pipe 4. In accordance with the invention the air pipe 4 and the conveyor pipe 2 are connected together through a by-pass pipe 5, in which is provided an adjustable valve 6 which may be constructed as an ordinary safety valve loaded by a weight 7, or in any other known manner. When the pressure of the compressed air reaches a predetermined degree the valve allows air to pass through the by-pass pipe 5 into the conveyor pipe 2 without entering the tank 1. The pressure at which the valve 6 opens may be adjusted according to the maximum pressure for which the compressor plant is constructed or it may be adjusted in accordance with the speed at which it is desired to empty the tank 1 as the time required to empty the tank 1

may be increased by reducing the pressure of the air in the tank.

In order to remove obstructions in the conveyor pipe 2 and thus prevent clogging thereof by-pass pipes 5 may be connected to 55 the conveyor pipe 2 at various points, so that compressed air can be supplied immediately in front of the clogged or obstructed point of the conveyor pipe 2, each such pipe being preferably provided with a valve so as to 60 enable it to be opened and closed as desired.

I claim as my invention:

Apparatus for conveying fine-grained materials comprising a closed tank, means to supply air under pressure to said tank, a 65 delivery pipe through which the material is delivered from the tank, a by-pass through which air may be delivered from the supply direct to the delivery pipe, and a safety valve interposed in the by-pass and adapted to permit air to pass from the air supply pipe directly into the delivery pipe when the pressure in the tank exceeds a predetermined degree. 70

This specification signed this 25th day of 75 June, A. D. 1931.
